UNITED STATES PATENT OFFICE

1,957,600

SHOE LACE FASTENER

George M. Kauffman, Baltimore, Md.

Application June 22, 1933, Serial No. 677,124

3 Claims. (Cl. 24—144)

This invention relates to an improved shoe lace fastener and seeks, among other objects, to provide a simple and efficient device of this character which, after the lace of a shoe has been tied, may be bent around the ends of the lace for neatly holding the end portions of the lace close against the shoe, thereby obviating the possibility of catching of the lace on objects against which the shoe may be brought in contact with consequent possible tripping or other injury to the wearer of the shoe.

The invention seeks, as a further object, to provide a device of this character embodying a ductile plate having tongues which may be readily bent about the ends of the shoe lace and whereby in a more rigid cap plate will be employed for securing the ductile plate in position on the shoe as well as provide a rigid member about which the tongues may be bent.

And the invention seeks, as a still further object, to provide a device well adapted for use in connection with conventional shoes and which may be readily applied.

With the foregoing and other objects in view, the invention consists in certain novel details of construction and combinations of parts hereinafter fully described and claimed, it being understood that various modifications may be resorted to within the scope of the appended claims without departing from the spirit or sacrificing any of the advantages of the invention.

In the drawing forming part of this specification, Figure 1 is a perspective view showing a conventional shoe equipped with a pair of my improved fastening devices.

Fig. 2 is a fragmentary front elevation more particularly showing the location of the fastening devices on the shoe.

Fig. 3 is a detail sectional view on the line 3—3 of Fig. 1.

Fig. 4 is a detail perspective view showing the parts of the fastener disassembled.

Fig. 5 is a detail sectional view showing a slight variation of the invention.

In carrying the invention into effect, I employ a ductile fastening plate 10 of lead or other suitable metal such as will withstand repeated bending without fracture. The body or central portion of the plate is substantially rectangular and extending from one longitudinal edge of the body, flush with the adjacent end edge thereof, is a tongue 11 while a similarly located tongue 12 extends from the opposite longitudinal edge of the body.

As shown in Figs. 1 and 2 of the drawing, a

pair of the plates 10 are mounted in the upper forward corners of a shoe upper adjacent the lace opening therein, being preferably disposed between the uppermost eyelets and the vertical edges of the upper at the lace opening. In the drawing, I have shown a conventional shoe at 13, the usual eyelets of the shoe at 14, and the lace at 15. Overlying the central body portions of the plates 10 are cap plates 16 which are preferably of suitable resilient sheet metal but in any event are rigid as compared with the plates 10. The plates 16 are rectangular to conform to the shape of the body portions of the plates 10 so as to terminate flush therewith, and extending through the plates 10 and 16 and through the shoe upper are rivets or other suitable fastening devices 17 rigidly securing the parts to the shoe.

As shown in Fig. 2 of the drawing, the tongues 11 of the fastening plates are normally straight so that the two ends of the lace 15 may be brought together across said plates and tied in the customary manner. The loops 18 thus formed, as well as the ends of the lace, are then bunched at each side of the shoe upper, when the tongues 11 of each of the fastening plates are bent over and across said loops and the ends of the lace, as shown in Fig. 1, for snugly securing the lace ends and the loops close against the shoe upper. Dangling of the lace ends so as to possibly catch in adjacent objects and trip the wearer of the shoe will thus be prevented while also, the shoe lace will be prevented from becoming untied. To untie the lace, however, it is simply necessary to grasp the ends thereof when a slight jerk on the lace will flex the tongues 11 to free the lace ends, when the shoe may be untied in the customary way.

In Fig. 5 of the drawing, I have illustrated a slight variation of the invention wherein I provide a U-shaped resilient clip 19 of suitable sheet metal. Overlying one end of the clip is a fastening plate 20 like the plate 10 and overlying the plate 20 is a cap plate 21 like the plate 16, rivets or other suitable fastening devices 22 being employed to secure the parts to the clip. Thus, as suggested in Fig. 5, the clip 19 may be engaged over the upper edge of the shoe upper, conventionally shown at 23, for connecting the lace fastener with the shoe. Otherwise, this variation of the invention is identical with the preferred construction and further description is accordingly believed unnecessary.

Having thus described the invention, I claim:

1. A shoe lace fastener including a fastening plate provided with oppositely directed ductile

tongues, and means extending through the plate and adapted to connect said plate with a shoe.

2. A shoe lace fastener including a ductile fastening plate provided with oppositely directed offset tongues, a rigid cap plate overlying the fastening plate, and means extending through the plates and adapted to connect said plates with a shoe.

3. The combination with a shoe having an upper provided with a lace opening, and a lace threaded through the upper at said opening, of

ductile fastening plates mounted upon the upper at opposite sides of said opening near the upper edge of the upper and each provided with oppositely directed offset tongues, rigid cap plates overlying the fastening plates, and fastening devices extending through the plates and securing said plates to the upper, said tongues being adapted to be bent about the ends of the lace when the lace is tied for securing the lace ends close against the upper.

GEORGE M. KAUFFMAN. [L. S.]
